UNITED STATES PATENT OFFICE.

JAMES F. DOWD, OF NEWPORT, RHODE ISLAND, ASSIGNOR OF ONE-HALF TO FRANK C. RICHARDS, OF NEWPORT, RHODE ISLAND.

BRUSH.

Application filed March 14, 1928. Serial No. 261,586.

This invention relates to brushes, and particularly to brushes intended for use in association with a water supply, capable of a great number of uses.

5 The brush may be used in a dry state, or with water, or it may even be employed in association with a vacuum producing means, in which event, a hollow handle may be connected to the suction creating means, although primarily, as stated, the brush is intended for use in scrubbing with water or the like.

15 It has been found in practice that the brush can be used for spraying vegetation in a garden or hothouse or the like, but its greatest utility, in so far as has been determined, is that as employed in cleaning or washing automobiles.

20 It is an object of this invention to provide a brush having a head with a cavity through which water may circulate to a plurality of nipples or openings, from whence it is discharged between tufts of the bristles of the brush.

25 It is furthermore an object of this invention to produce a brush having tufts of bristles, associated with means that are removably mounted in the head, and in which provision is made for the circulation of water, as aforesaid.

It is furthermore an object to produce a brush of this type which will be durable and efficient.

35 With the foregoing and other objects in view, the invention consists in the details of construction, and in the arrangement and combination of parts to be hereinafter more fully set forth and claimed.

40 In describing the invention in detail, reference will be had to the accompanying drawings forming part of this application, wherein like characters denote corresponding parts in the several views, and in which—

45 Figure 1 illustrates a sectional view of a brush embodying the invention;

Figure 2 illustrates a plan view of one of the elements;

50 Figure 3 illustrates an enlarged sectional view of a fragment of said element; and

Figure 4 illustrates a sectional view of a modified construction.

55 In these drawings, 5 denotes a head having an opening 6 for the reception of a handle 7, which is in the nature of a pipe

adapted to be connected to a source of water supply. As it is old to provide pipes in association with water supplies or couplings leading thereto, it is believed unnecessary to illustrate the details of the parts that are 60 associated with the handle for furnishing water.

The head has a cavity 8 to which water is delivered and it is also provided with an internally threaded flange 9 and a shoulder 10. The shoulder is adapted to be engaged by a gasket or packing 11 for effecting a water-tight joint between the head and a unit of the brush, to be presently described.

In the present embodiment of the invention, a disk 12 of appropriate thickness has a peripheral threaded portion 13 which is threaded into the flange of the head, and the said disk is further provided with a peripheral flange 14 fitting against the lower 70 edge of the flange of the head. Recesses 15 are formed in the peripheral flange in order that a spanning wrench or other implement for imparting motion to the disk may be employed in installing or removing 75 the disk from the head. The disk is also provided with a plurality of apertures 16 which taper from the inner to the outer surface of the disk and these apertures aline or register with apertures 17 formed in a brush plate 18 which is assembled with the disk as a brush unit. The plate 18 may carry a plurality of brush tufts 19 which as to number is immaterial.

80 Nipples or tubes 20 are arranged in the apertures of the disk and plate and preferably they project at the outer surface of the plate, and the ends preferably are shaped or upset to form flanges 21 which serve to hold the disk and plate assembled. Owing to the 85 tapered contour of the apertures of the disk and the fact that the nipples are shaped to those contours, a wedging action results between the nipples and the disk, which serves, in association with the flanges, to 90 retain the parts assembled.

95 Since the brush unit may be removably applied to the head, brush units of different qualities or characteristics may be employed in association with one head. For rough 100 work, a brush unit with relatively heavy bristles may be employed, whereas where polishing or other delicate operations are to be performed, bristles of different texture and quality may be used.

In that form of the invention illustrated in Figure 4, the head 22 has a connection 23 for a hollow handle and it also has an apertured bottom wall 24 with depending hollow nipples 25. The brush element 26 has apertures 27 to receive the nipples and the said brush element is secured to the head by fastenings 28, such as screws, and there is an interposed packing 29 to effect a tight joint 10 between the brush element and the head.

I claim:

In a fountain brush, a head having a cavity, a hollow handle attached to the head and communicating with the cavity, the said 15 head having a threaded inner wall below the cavity, a brush unit comprising a disk having tapered apertures, said brush element

having a threaded peripheral portion engaging the threads of the brush unit and a flange extending under the brush unit at 20 its periphery, a plate coextensive with the under surface of the brush unit having brush elements attached thereto associated with the said disk and having apertures lining with the apertures of the disk, tubular members fitting the apertures of the disk and projecting through the apertures of the plate the ends of said tubes being flanged to engage the outer surface of the plate for holding the plate and disk assembled, and a 30 gasket interposed between said brush unit and the head.

JAMES F. DOWD.
